CLAIM

The ornamental design for an exercise tire, as shown and described.

DESCRIPTION

FIG. 1 is a perspective view of an exercise tire;
 FIG. 2, is a front view of the exercise tire of FIG. 1;
 FIG. 3 is a rear view of the exercise tire of FIG. 1;
 FIG. 4 is a right side view of the exercise tire of FIG. 1;
 FIG. 5 is a left side view of the exercise tire of FIG. 1;
 FIG. 6 is a top view of the exercise tire of FIG. 1; and,
 FIG. 7 is a bottom view of the exercise tire of FIG. 1.
 The broken lines showing portions of the exercise tire form no part of the claim.
